COMBINED BOW LIGHT, DECK CLEAT AND FLAGSTAFF

Edward William Sanger, Port Lambton, Ontario, and Geoffrey Frederick Clark, Wallaceburg, Ontario, Canada, assignors to Schultz Die Casting Company of Canada Limited, Wallaceburg, Ontario, Canada

Application January 9, 1959, Serial No. 54,095

Term of patent 3½ years

(Cl. D48—32)

FIG. 3

FIG. 4

FIG. 2

Fig. 1 is a perspective view of a combined bow light, deck cleat and flagstaff showing our new design;

Fig. 2 is a perspective view thereof as seen from the left of Fig. 1;

Fig. 3 is an enlarged cross-sectional view taken through the line 3—3 of Fig. 2;

Fig. 4 is an enlarged cross-sectional view taken through the line 4—4 of Fig. 2; and

Fig. 5 is a front elevational view of the article with the flagstaff fragmentarily shown for convenience of illustration.

We claim:

The ornamental design for a combined bow light, deck cleat and flagstaff, as shown.
